United States Patent Office.

PURMERT BRADFORD, OF NEW HAVEN, CONNECTICUT, ASSIGNOR TO
SARGENT & CO., OF SAME PLACE.

Letters Patent No. 61,707, dated February 5, 1867.

IMPROVEMENT IN ORNAMENTING COFFIN SCREWS.

The Schedule referred to in these Letters Patent and making part of the same.

TO ALL WHOM IT MAY CONCERN:

Be it known that I, P. BRADFORD, of New Haven, in the county of New Haven, and State of Connecticut, have invented a new Improvement in Ornament for Coffin Screw Heads; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view; and in

Figure 2, a longitudinal central section enlarged.

My invention is designed to cover the head of a common screw or nail after it has been inserted, giving it the appearance of a richly ornamented head, and is designed more particularly for coffin screws, but equally applicable wherever such an ornamented head is desired.

To enable others to construct and use my improvement, I will proceed to describe the same as illustrated in the accompanying drawings.

A is a plate of any desired form or configuration, formed from thin sheet metal, in the usual manner of forming sheet-metal ornaments, pierced in the centre at D to receive a screw or nail, as denoted in blue, fig. 2. F is the cap or cover, also of any desired form or configuration, similarly formed, and is hinged to the plate A at E by forming a tongue, e, on the cap, as denoted in red, fig. 1, and inserting it through a hole in the plate A, as seen in fig. 2. Upon the opposite side of the cap, I form a tongue, N, bent in the form as seen in fig. 2, and pierce the plate so that the tongue N may be easily pressed therethrough, the natural elasticity of the metal causes this tongue N to act as a spring or latch, and securely hold the cap upon the plate, as denoted in black, fig. 2. By depressing the said tongue or spring N the cap may be opened, as denoted in red, fig. 2, for the insertion of the screw or nail, as denoted in blue, and after the screw has been so inserted, turn down the cap, press the tongue or spring N through the plate A, as denoted in black, and the cap will be securely retained in its position on the plate, and have the appearance of a large ornamental head, the screw or nail serving to secure the plate.

I am aware that ornamental heads of this character have before been made, but always with a different manner of securing the cap to the plate; that is to say, the manner of securing the cap was apparent from the outside, and the cap hinged to the plate by a rivet, as seen the patent of A. B. Bailey, October 14, 1862, which adds much to the cost of manufacture. By my improvement the use of the rivet is entirely dispensed with and the security positive and concealed.

I do not therefore broadly claim an ornamental detached cap for coffin screws, but having thus fully described my invention, what I do claim as new and useful, and desire to secure by Letters Patent, is—

The cap F provided with a tongue, N, so as to be secured to the plate A, substantially in the manner and for the purpose herein set forth.

PURMERT BRADFORD.
